US0D1110313S

(12) **United States Design Patent** (10) **Patent No.:** **US D1,110,313 S**
(45) **Date of Patent:** **** Jan. 27, 2026**

(54) **ELECTRONIC DEVICE**

- (71) Applicant: **Intel Corporation**, Santa Clara, CA (US)
- (72) Inventors: **Alex Gilpin**, Hillsboro, OR (US); **May Chan**, Portland, OR (US); **Michael Hyde**, Santa Rosa, CA (US); **Andrew Hooper**, Santa Clara, CA (US)
- (73) Assignee: **Intel Corporation**, Santa Clara, CA (US)
- (**) Term: **15 Years**

(21) Appl. No.: **29/881,173**

(22) Filed: **Dec. 28, 2022**

(51) LOC (15) Cl. **14-01**

(52) U.S. Cl.

USPC **D14/341**

(58) **Field of Classification Search**

USPC D14/314, 345, 346, 356, 371, 341, 300, D14/138
CPC G06F 1/16; G06F 1/1601; G06F 1/1615; G06F 1/1616; G06F 1/1618; G06F 1/1624; G06F 1/1633

(57) **CLAIM**

The ornamental design for an “electronic device” as shown and described.

DESCRIPTION

FIG. 1 is a front perspective view of an electronic device. FIG. 2 is a rear perspective view of the electronic device of FIG. 1.

FIG. 3 is a front view of the electronic device of FIG. 1.

FIG. 4 is a rear view of the electronic device of FIG. 1.

FIG. 5 is a top view of the electronic device of FIG. 1.

FIG. 6 is a bottom view of the electronic device of FIG. 1.

FIG. 7 is a left side view of the electronic device of FIG. 1; and,

FIG. 8 is a right side view of the electronic device of FIG. 1.

The features shown in broken lines form no part of the claimed design.

1 Claim, 8 Drawing Sheets
